UNITED STATES PATENT OFFICE.

CHARLES J. AHRENFELDT, OF NEW YORK, N. Y.

DESIGN FOR A COVERED DISH.

SPECIFICATION forming part of Design No. 30,525, dated April 11, 1899.

Application filed January 11, 1899. Serial No. 701,891. Term of patent 3½ years.

To all whom it may concern:

Be it known that I, CHARLES J. AHRENFELDT, a citizen of the United States, residing in the city of New York, county of New York, and State of New York, have invented and produced a new and original Design for a Covered Dish, of which the following is a specification, reference being had to the accompanying drawings, forming a part hereof, like letters referring to like parts in each figure of the same.

In the said drawings, Figure 1 is a side view of a covered dish embodying my design. Fig. 2 is a plan view of the cover. Fig. 3 is a plan view of the dish with cover removed. Fig. 4 is an end view of the dish and cover. Fig. 5 is a vertical section of the same on the line 5 5 of Fig. 3.

The cover A has four sets of indentations B in its brim, giving its periphery a wave-like contour, with three small waves and one large wave alternated. On the under side of said brim is a ledge C, running around the same, parallel with its periphery and having the same wave-like contour. It is also parallel to the upper edge D of the dish, within which it fits. The indentations of the upper edge D are carried down the sides of the dish, forming the furrows E on its outer surface, which extend down to the base F, the said base being of corresponding contour to the upper edge.

The cover has furrows G running from the

indentations in the periphery toward the handle H, where they are merged in the surface. 35

The handle is of oval form, with a depressed portion at the upper part in the center, and is provided with leafed ornamentations I. On either side of the handle, on the upper surface of the cover, is a fillet-like ornament J, 40 and a little farther removed therefrom, on either side, is another ornament K, which consists of a centerpiece k of combined escalloped and arabesque ornamentations, with leafed ornaments k' on either side and a rosette k² beneath said centerpiece with leafed ornaments on either side of it. A similar ornament K' is found at either end of the handle on the upper surface of the cover.

The base is provided on either side with 50 three small ornaments L.

The handles M of the dish project from either end of the same at the bulged portion thereof and are ornamented similarly to the handle H of the cover, having also beneath them, on the outer surface of the dish, two fillet-like ornaments N and an acorn-like ornament N'.

What I claim is—

The design for a covered dish herein shown and described. 60

Signed at the city of New York this 4th day of January, 1899.

CHARLES J. AHRENFELDT.
